(57) **CLAIM**

The ornamental design for an LED chip, as shown and described.

DESCRIPTION

FIG. 1 is a 3D view of a LED chip according to an embodiment of the present disclosure in which the cover plate is transparent and the holes penetrate through the cover plate and expose the electrode;

FIG. 2 is another 3D view of the LED chip according to the embodiment of the present disclosure;

FIG. 3 is a top view of the LED chip according to the embodiment of the present disclosure;

FIG. 4 is a left-side view of the LED chip shown in FIG. 3; FIG. 5 is a right-side view of the LED chip shown in FIG. 3;

FIG. 6 is a front-side view of the LED chip shown in FIG. 3;

FIG. 7 is a rear-side view of the LED chip shown in FIG. 3; FIG. 8 is a bottom view of the LED chip shown in FIG. 3; FIG. 9 is a 3D view of a LED chip according to another embodiment of the present disclosure;

FIG. 10 is another 3D view of the LED chip according to the another embodiment of the present disclosure;

FIG. 11 is a top view of the LED chip according to the another embodiment of the present disclosure;

FIG. 12 is a left-side view of the LED chip shown in FIG. 11;

FIG. 13 is a right-side view of the LED chip shown in FIG. 11;

FIG. 14 is a front-side view of the LED chip shown in FIG. 11;

FIG. 15 is a rear-side view of the LED chip shown in FIG. 11; and,

FIG. 16 is a bottom view of the LED chip shown in FIG. 11.
